UNITED STATES PATENT OFFICE.

RANSOM C. WRIGHT, OF PHILADELPHIA, PENNSYLVANIA, AND FRANK E. STEBBINS, OF WASHINGTON, DISTRICT OF COLUMBIA.

CAR-TRUCK CONSTRUCTION.

SPECIFICATION forming part of Letters Patent No. 769,369, dated September 6, 1904.

Application filed February 5, 1904. Serial No. 192,103. (No model.)

To all whom it may concern:

Be it known that we, RANSOM C. WRIGHT, residing at Philadelphia, in the county of Philadelphia and State of Pennsylvania, and FRANK E. STEBBINS, residing at Washington, District of Columbia, citizens of the United States, respectively, have invented certain new and useful Improvements in Car-Truck Construction, of which the following is a specification.

Our invention relates to car-truck frames, the objects being, first, the production of a frame which can easily be constructed in the ordinary car-shop without the use of special tools and appliances and which may be repaired with equal facility, and, secondly, the provision of an improved cast-metal pedestal which shall have a detachable end jaw to allow the removal of a pair of wheels and an axle at the end of the frame.

With the above main ends in view our invention consists in certain novelties of construction and combinations of parts hereinafter set forth and claimed.

The accompanying drawings illustrate one complete truck-frame and two examples of slightly-different cast-metal pedestals constructed according to the best modes we have so far devised for the practical application of the principles.

Figure 1 is a side view in elevation. Fig. 2 is a top plan view of one-half of the frame shown on Fig. 1, one side being a section on line *a a*, Fig. 1. Fig. 3 shows a pedestal with a removable end jaw. Fig. 4 is a front end view of Fig. 3. Fig. 5 is a rear end view. Fig. 6 is a top plan view. Fig. 7 is a bottom plan view. Fig. 8 is a section on line *b b*, Fig. 3. Fig. 9 is a side view of a cast-metal side piece with one of the pedestals in section, the pedestal being substantially identical with that shown in Figs. 3, 4, 5, 6, and 7, but integral with the side piece. Fig. 10 is an end view of the pedestal. Fig. 11 is a section on line *x x* of Fig. 9. Fig. 12 is a section on line *y y*.

The first two sheets of the drawings show a truck-frame with I-beam side pieces, channel-beam transoms, and cast-metal pedestals having flanged necks secured upon the ends of the I-beam sides and with openings at the

bottoms of the jaws for the removal of the journal-boxes. The third sheet shows the preferred type of pedestal with a removable end jaw. The side pieces and transoms, being the same as those in Sheets 1 and 2, are not reproduced in full. The fourth sheet illustrates the removable end jaw, spring-pocket, longitudinally-perforated horizontal extension beneath the journal-box, bolts, and inner bearing-flange of the pedestal shown on Sheet 3 embodied in an integral cast side piece.

Referring to the first three sheets, the numeral 1 designates the axles; 2, the wheels; 3, the journals; 4, the journal-boxes; 5, helical springs located above the journal-boxes and supporting the frame; 6, I-beam side pieces, preferably such as are rolled and for sale in open market; 7, the top flanges of the I-beam; 8, the bottom flanges; 9, the top and bottom flanges on the inside ends of the beams with their edges cut away substantially the length of the neck of the pedestal; 10, the transoms, in this instance of rolled channel-sections; 11, channel-tie pieces adjacent the centers of the transoms and riveted to the webs thereof; 12, a bottom center tie-plate riveted to the flanges of the transoms; 13, a top center tie-plate riveted to the top flanges of the transoms; 14, connection-angles riveted to the webs of the transoms and to the webs of the side pieces; 15, bottom gusset-plates riveted to the flanges of the transoms and the sides; 16, the top gusset-plates riveted to the flanges of the transoms and sides; 17, the ends of the transom-webs resting on the lower flange of an I-beam side piece, the top and bottom flanges of the ends of the transoms being cut away to allow the edge of the web to abut against the web of a side piece; 18, pedestal-necks; 19, the top flange of a neck; 20, the perpendicular flange above the flange of the neck for strengthening the same; 21, a lower flange of the neck; 22, the perpendicular strengthening-flange for the lower flange of the neck; 23, the web of the neck which engages the surface of the end of a side piece; 24, recesses for the cut-away top and bottom inner flanges of the end of the I-beam side piece; 25, the inner journal-box bearing flange or jaw of the pedestal; 26, the

spring-pocket, in this case cast integral with the pedestal; 27, rivets passed through the webs of the pedestal-necks and ends of the I-beam; 28, rivets passed through the upper 5 flange of the neck and upper flange of the I-beam, and 29 rivets passed through the lower flange of the neck and lower flange of the I-beam.

Referring to Figs. 1 and 2, the numeral 10 30 designates the perforated end of the inner jaw; 31, the outer jaw, I-shaped in cross-section; 32, the bearing-flange of the outer jaw; 33, the perforated lower end of the outer jaw; 34, a tube or spacing-piece between the jaws; 15 35, a tie-bolt engaging the jaws and spacing-piece, and 36 is a nut.

Referring to Figs. 3 to 8 and 9 to 12, the numeral 37 designates the perforated head of the pedestal; 38, recesses in the pedestal-head 20 for the upper end of the removable outer jaw; 39, the horizontal extension beneath the journal-box, preferably cored out to secure lightness of weight; 40, holes for a bolt in the horizontal extension; 41, a recess for the 25 lower end of the removable outer jaw; 42, the removable outer jaw; 43, the bearing-flange of the outer jaw for engaging the recess in the side of the journal-box; 44, the lower perforated end of the jaw; 45, a projection or lug 30 on the end of the removable jaw to engage the recess 41 in the end of the horizontal extension; 46, a horizontally-disposed threaded bolt; 47, a nut for the bolt; 48, the perforated forked upper end of the removable jaw, the 35 ends being seated in the recesses 38, so that the outward stresses will be taken by the pedestal-head; 49, a bolt passed through the forked upper end of the jaw and the pedestal-head, and 50 is a nut which, being turned, forces 40 the forked ends into frictional contact with the surfaces bounding the recess 38 in the pedestal-head.

In the frame shown by the first three sheets the upper or lower flange of the pedestal-neck 45 may in some cases be omitted, the spring-pocket be replaced by a flat or shallow spring-bearing or by a bearing made separate, and the necks of the pedestals be located upon the outer surfaces of the ends of the I-beam side pieces. 50 In practice the integral spring-pocket is the preferable construction, as it allows the omission of the top flange over the pedestal-head, and, furthermore, it increases the strength of the pedestal at its weakest point—that is, at 55 the section where the weight of the load is transmitted from the side piece to the spring and journal-box. The pocket for the spring, as shown in the views, has edges inclined toward the ends of the I-beam, thus increasing 60 the amount of metal adjacent the inner bearing-flange and web of the pedestal.

On Sheet 4 the main novel features of the preferred type of pedestal with removable end jaw are embodied in a pedestal integral 65 with a side piece.

From the foregoing description, taken in connection with the drawings, it is obvious that we have produced a truck-frame and a novel type of pedestal with a removable end jaw which fulfills all the conditions set forth as 70 the main ends of our invention.

Modifications and changes may of course be introduced in the physical embodiment of our improvements by the manufacturer and without constituting substantial departures. 75

What we claim is—

1. The combination in a truck-frame structure, of a transom or transoms located between the pairs of wheels and adapted to support a car-body; two I-beam side pieces united at 80 points between their ends directly to the ends of the transom or transoms, each end of each side piece having its flanges and web provided with holes; and cast-metal pedestals each having an outer jaw and an inner jaw with bearing-flanges, a neck or extension at right angles to the jaws with a perforated top flange 85 a perforated bottom flange and a web, and said pedestals secured to the vertical ends of the side pieces by rivets which pass through the top and bottom flanges and webs of each pedestal-neck and end of the side piece; and detachable means for closing the journal-box openings in the pedestals. 90

2. The combination in a truck-frame structure, of a transom or transoms located between the pairs of wheels and adapted to support the end of a car-body; two I-beam side pieces united at points between their ends directly to the ends of a transom or transoms, each 95 end of each side piece having its upper flange and web provided with holes; and cast-metal pedestals each having an outer jaw and an inner jaw with bearing-flanges, a neck or extension at right angles to the jaws with a 100 perforated top flange and a web, and said pedestals secured to the vertical ends of the side pieces by rivets which pass through the top flanges and webs of each pedestal-neck and end of a side piece; and detachable means 105 for closing the journal-box opening in the pedestal. 110

3. The combination in a truck-frame structure, of a transom or transoms located between the pairs of wheels and adapted to support the 115 end of a car-body; two I-beam side pieces united at points between their ends directly to the transom or transoms, each end of each side piece having its bottom flange and web provided with holes; and cast-metal pedestals each having an outer jaw and an inner 120 jaw with bearing-flanges, a neck or extension at right angles to the jaws with a perforated bottom flange and a web, and said pedestals secured to the vertical ends of the side pieces by 125 rivets which pass through the bottom flanges and webs of each pedestal-neck and end of a side piece; and detachable means for closing the journal-box openings in the pedestals. 130

4. The combination in a truck-frame struc-

ture, of a transom or transoms located between the pairs of wheels and adapted to support the end of a car-body; two I-beam side pieces united at points between their ends directly to the ends of the transom or transoms, each end of each side piece having its flanges and web provided with holes; gusset-plates riveted to the flanges of the side pieces and transom or transoms; and cast-metal pedestals each having an outer jaw and an inner jaw with bearing-flanges, a neck or extension at right angles to the jaws with a perforated top flange a perforated bottom flange and a web, and said pedestals secured to the vertical ends of the side pieces by rivets which pass through the top and bottom flanges and webs of each pedestal-neck and end of a side piece; and detachable means for closing the journal-box openings in each pedestal.

5. The combination in a truck-frame structure, of a transom or transoms located between the pairs of wheels and adapted to support the end of a car-body; two I-beam side pieces united at points between their ends directly to the ends of the transom or transoms, each end of each side piece having its upper flange and web provided with holes; and cast-metal pedestals each having an outer jaw and an inner jaw with bearing-flanges, a neck or extension at right angles to the jaws with a perforated top flange and a web, and said pedestals secured to the vertical ends of the side pieces by rivets which pass through the top flanges and webs of each pedestal-neck and end of a side piece; and detachable means for closing the journal-box openings in the pedestals.

6. The combination in a truck-frame structure, of a transom or transoms located between the pairs of wheels and adapted to support the end of a car-body; two I-beam side pieces united at points between their ends directly to the ends of the transom or transoms, each end of each side piece having its bottom flange and web provided with holes; gusset-plates united to the flanges of the side pieces and transom or transoms; and cast-metal pedestals each having an outer jaw and an inner jaw with bearing-flanges, a neck or extension at right angles to the jaws with a perforated bottom flange and a web, and said pedestals secured to the vertical ends of the side pieces by rivets which pass through the bottom flanges and webs of each pedestal-neck and end of a side piece; and detachable means of closing the journal-box openings in the pedestals.

7. The combination in a truck-frame structure, of a transom or transoms located between the pairs of wheels and adapted to support the end of a car-body; two I-beam side pieces united at points between their ends directly to the ends of the transom or transoms, each end of each side piece having its flanges and

web provided with holes; and cast-metal pedestals each having an outer jaw and an inner jaw with bearing-flanges, a seat or bearing for a spring, a neck or extension at right angles to the jaws with a perforated top flange a perforated bottom flange and a web, and said pedestals secured to the vertical ends of the side pieces by rivets which pass through the top and bottom flanges and webs of each pedestal-neck and end of a side piece; and detachable means for closing the journal-box openings in the pedestals.

8. The combination in a truck-frame structure, of a transom or transoms located between the pairs of wheels and adapted to support the end of a car-body; two I-beam side pieces united at points between their ends directly to the ends of the transom or transoms, each end of each side piece having its upper flange and web provided with holes; and cast-metal pedestals each having an outer jaw and an inner jaw with bearing-flanges, a seat or bearing for a spring, a neck or extension at right angles to the jaws with a perforated top flange and a web, and said pedestals secured to the vertical ends of the side pieces by rivets which pass through the top flanges and webs of each pedestal-neck and end of a side piece; and detachable means for closing the journal-box openings in the pedestals.

9. The combination in a truck-frame structure, of a transom or transoms located between the pairs of wheels and adapted to support the end of a car-body; two I-beam side pieces united at points between their ends directly to the ends of a transom or transoms, each end of each side piece having its bottom flange and web provided with holes; and cast-metal pedestals each having an outer jaw and an inner jaw with bearing-flanges, a seat or bearing for a spring, a neck or extension at right angles to the jaws and a perforated bottom flange and a web and said pedestals secured to the vertical ends of the side pieces by rivets which pass through the bottom flanges and webs of each pedestal-neck and end of a side piece; and detachable means for closing the journal-box openings in the pedestals.

10. The combination in a truck-frame structure, of a transom or transoms located between the pairs of wheels and adapted to support the end of a car-body; two I-beam side pieces united at points between their ends directly to the ends of a transom or transoms, each end of each side piece having its flanges and web provided with holes; and cast-metal pedestals each having an outer jaw and an inner jaw with bearing-flanges, an integral pocket for a spring, a neck or extension at right angles to the jaws with a perforated top flange, perforated bottom flange and a web, and said pedestals secured to the vertical ends of the side pieces by rivets which pass through the top and bottom flanges and webs of each pedestal-

neck and end of a side piece; and detachable means for closing the journal-box openings in the pedestals.

11. The combination in a truck-frame structure, of a transom or transoms located between the pairs of wheels and adapted to support the end of a car-body; two I-beam side pieces united at points between their ends directly to the ends of a transom or transoms, each end 10 of each side piece having its upper flange and web provided with holes; and cast-metal pedestals each having an outer jaw and an inner jaw with bearing-flanges, an integral pocket for a spring, a neck or extension at right angles to the jaws, with a perforated top flange and a web, and said pedestals secured to the vertical ends of the side pieces by rivets which pass through the top flanges and webs of each pedestal-neck and end of a side piece; and detachable means for closing the journal-box openings in the pedestals.

12. The combination in a truck-frame structure, of a transom or transoms located between the pairs of wheels and adapted to support the end of a car-body; two I-beam side pieces united at points between their ends directly to the ends of the transom or transoms, each end 20 of each side piece having its bottom flange and web provided with holes; and cast-metal pedestals each having an outer jaw and an inner jaw with bearing-flanges, an integral pocket for a spring, a neck or extension at right angles to the jaws with a perforated bottom flange and a web, and said pedestals secured 30 to the vertical ends of the side pieces by rivets which pass through the bottom flanges and webs of each pedestal-neck and end of a side piece; and detachable means for closing the journal-box openings in the pedestals.

13. The combination in a truck-frame structure, of two flanged beam-transoms located between the pairs of wheels and adapted to support the end of a car-body; two I-beam side pieces united at points between their ends 40 directly to the ends of the flanged transom-beams by gusset-plates and connection-angles, each end of each side piece having its flanges and web provided with holes; and cast-metal pedestals each having an outer jaw and an inner jaw with bearing-flanges, a neck or extension at right angles to the jaws with a perforated top flange a perforated bottom flange and a web, and said pedestals secured to the vertical ends of the side pieces by rivets which 50 pass through the top and bottom flanges and webs of each pedestal-neck and end of a side piece; and detachable means for closing the journal-box openings in the pedestals.

14. The combination in a truck-frame structure, of two flanged beam-transoms located between the pairs of wheels and adapted to support the end of a car-body; two I-beam side pieces united at points between their ends 60

directly to the ends of the flanged transom-beams by gusset-plates and connection-angles, 65 each end of each side piece having its upper flange and web provided with holes; and cast-metal pedestals each having an outer jaw and an inner jaw with bearing-flanges, a neck or extension at right angles to the jaws with a perforated upper flange and a web, and said pedestals secured to the vertical ends of the side pieces by rivets which pass through the upper flanges and webs of each pedestal-neck and end of a side piece; and detachable means 75 for closing the journal-box openings in the pedestals.

15. The combination in a truck-frame structure, of two flanged beam-transoms located between the pairs of wheels and adapted to support the end of a car-body; two I-beam side pieces united at points between their ends directly to the ends of the flanged transom-beams by gusset-plates and connection-angles, 80 each end of each side piece having its bottom flange and web provided with holes; and cast-metal pedestals each having an outer jaw and an inner jaw with bearing-flanges, a neck or extension at right angles to the jaws with a perforated bottom flange and a web, 90 and said pedestals secured to the vertical ends of the side pieces by rivets which pass through the bottom flanges and webs of each pedestal-neck and end of a side piece; and detachable means for closing the journal-box openings in 95 the pedestals.

16. The combination in a car-truck frame, of side pieces I-shaped in cross-section; a flanged transom or transoms uniting the side pieces adjacent their centers; and cast-metal pedestals each having an inner flange or wall 100 25, a seat or pocket for a spring, a web, and top and bottom flanges secured to the top and bottom flanges of the side pieces and independent of a transom; said top flange, bearing flange or wall, web and spring seat or pocket of the pedestal being integral.

17. The combination in a car-truck frame, of side pieces I-shaped in cross-section; a transom or transoms uniting the side pieces 110 adjacent their centers; and cast-metal pedestals each having an inner bearing flange or wall 25, an outer flanged jaw, a seat or pocket for a spring, top and bottom flanges and a web secured to the top and bottom flanges and webs of the side pieces independent of the transom or transoms; said top flange, inner bearing flange or wall, spring seat or pocket and web of a pedestal being integral.

18. The combination in a car-truck frame, 120 of side pieces I-shaped in cross-section; a transom or transoms uniting the side pieces adjacent their centers; and cast-metal pedestals each having an inner bearing flange or wall 25, top flange and a web, and secured to 125 the flanges and webs of the side pieces inde-

pendent of a transom or transoms; said inner bearing flange or wall, top flange, and web of a pedestal being integral.

19. The combination of a car-truck frame, 5 of side pieces I-shaped in cross-section; a transom or transoms uniting the side pieces adjacent their centers; and cast-metal pedestals each having a web engaging the side of the I-beam, and top and bottom flanges secured to the top and bottom flanges of the side pieces by rivets passed through the flanges of the pedestals and side pieces; said pedestals being secured in position independent of the transom or transoms.

15 20. The combination in a car-truck frame, of side pieces I-shaped in cross-section; a transom or transoms uniting the side pieces adjacent their centers by top gusset-plates and connection-angles; and cast-metal pedestals each formed with a spring-seat, bearing wall or flange 25 and having top and bottom flanges and a web; said pedestals being secured to the top and bottom flanges of the side pieces by rivets and each pedestal being independent of a transom and located at the end of a side piece so that the bearing flange or wall 25 will be in a perpendicular plane beyond the end of a side piece.

21. The combination in a car-truck frame, 30 of I-beam side pieces having the edges of their flanges at the ends removed; a transom or transoms rigidly uniting the side pieces adjacent their centers and cast-metal pedestals with recessed necks secured upon the vertical ends of the side pieces.

35 22. The combination with I-beam side pieces and flanged transoms, of cast-metal pedestals each having a bearing wall or flange 25, a spring seat or pocket, a web, and a top flange all cast integral, and a lower flange secured to the lower flange of the I-beam; said pedestals being independent of a transom, whereby a pedestal may be removed and another substituted without disarranging a transom.

45 23. The combination with the flanged end of a truck-frame side piece, of a cast-metal pedestal having flanged jaws, means for closing the opening for the insertion of a journal-box, and a neck or extension at right angles to the jaws provided with top and bottom flanges and a single web, the said web being located between the top and bottom flanges of the side piece.

24. A cast-metal pedestal having outer and 55 inner flanged jaws, a neck or extension at right angles to the jaws provided with a top flange, a bottom flange, a web, and two recesses for the flanges of the side piece; and means for closing the opening in the pedestal for the insertion of the journal-box.

25. A cast-metal pedestal having outer and inner flanged jaws, a neck or extension at right angles to the jaws provided with a top flange, a bottom flange, a web, a recess for the flange

of a side piece, and a bearing or seat for a 65 spring.

26. A cast-metal pedestal having outer and inner flanged jaws, a neck or extension at right angles to the jaws provided with a top flange, a bottom flange, a web and a pocket with inclined edges for a spring, said pocket cast integral with the pedestal. 70

27. A cast-metal pedestal having outer and inner flanged jaws, a neck or extension at right angles to the jaws provided with a top flange 75 a bottom flange, a web, a perforated horizontal extension beneath the journal-box, and a horizontal bolt, the outer jaw being detachable and secured at its lower end by the bolt.

28. A cast-metal pedestal having outer and inner flanged jaws, the outer jaw being forked at one end and perforated at the other end, a neck or extension at right angles to the jaws provided with a bottom flange and a web, a seat for a spring, a longitudinally-perforated 85 horizontal extension, and two bolts for securing the ends of the removable jaw.

29. A cast-metal pedestal having a perforated head, outer and inner flanged jaws, the outer jaw being removable and having a forked 90 perforated end, a neck or extension at right angles to the jaws provided with a top flange and a web, a horizontally-perforated extension beneath the journal-box, and two bolts securing the ends of the removable jaw, one 95 of the bolts being located longitudinally in the horizontal extension.

30. A cast-metal pedestal having outer and inner flanged jaws, the outer jaw being removable, a neck or extension at right angles to the 100 jaws, provided with a bottom flange and a web, perforated head, and a longitudinally-perforated horizontal extension beneath the journal-box to receive a horizontal bolt.

31. A cast-metal pedestal having outer and inner flanged jaws, the outer jaw being removable and having perforated ends, a neck or extension at right angles to the jaws provided with a top flange, a bottom flange, and a web, a seat or bearing for a spring, a longitudinally-perforated horizontal extension; a perforated head with recesses, and two bolts. 105

32. A cast-metal pedestal having an inner bearing-flange, a longitudinally-perforated rigid horizontal extension, a neck with a web 110 and two flanges located upon one side of the web forming a recess for the end of a side piece, a perforated head, a removable outer flanged jaw perforated at the ends, a bolt located in the horizontal extension and securing the lower end of the outer jaw, and a bolt securing the upper end of the removable jaw to the head. 120

33. A cast-metal pedestal having an inner bearing-flange, a longitudinally-perforated 125 rigid horizontal extension, a neck with a web and two flanges located upon one side of the web forming a recess for the end of a side

piece, a perforated head, a removable outer flanged jaw perforated at the ends, a bolt located in the horizontal extension and securing the lower end of the outer jaw, and a bolt 5 securing the upper end of the removable jaw to the head; said pedestal having a seat for a spring.

34. A cast-metal pedestal having an inner bearing-flange, a longitudinally-perforated rigid horizontal extension, a neck with a web and two flanges located upon one side of the web forming a recess for the end of a side piece, a perforated head, a removable outer flanged jaw perforated at the ends, a bolt located in the horizontal extension and securing the lower end of the outer jaw, and a bolt 10 securing the upper end of the removable jaw to the head; said outer jaw having a forked upper end.
35. A cast-metal pedestal having an inner bearing-flange, a longitudinally-perforated rigid horizontal extension, a neck with a web and two flanges located upon one side of the web forming a recess for the end of a side piece, a perforated head, a removable outer flanged jaw perforated at the ends, a bolt located in the horizontal extension and securing the lower end of the outer jaw, and a bolt 15 securing the upper end of the removable jaw to the head; said outer jaw having a forked upper end.
36. A cast-metal pedestal having an inner bearing-flange, a longitudinally-perforated rigid horizontal extension, a neck with a web and two flanges located upon one side of the web forming a recess for the end of a side piece, a perforated head, a removable outer flanged jaw perforated at the ends, a bolt located in the horizontal extension and securing the lower end of the outer jaw, and a bolt 20 securing the upper end of the removable jaw to the head; said pedestal having an integral spring-pocket.

37. A pedestal having a longitudinally-perforated rigid horizontal extension, a perforated head with recesses, a removable flanged end jaw with perforated ends, a bolt located longitudinally in the horizontal extension and securing the lower end of the removable jaw; and a bolt 30 securing the upper end of the jaw to the head.

38. A pedestal having a longitudinally-perforated rigid horizontal extension, a perforated head with recesses, a removable flanged end jaw with perforated ends, a bolt located longitudinally in the horizontal extension and securing the lower end of the removable jaw; and a bolt 40 securing the upper end of the jaw to the head; said pedestal having an integral spring-pocket.

39. A pedestal having a longitudinally-perforated rigid horizontal extension, a perforated head with recesses, a removable flanged end jaw with perforated ends, a bolt located longitudinally in the horizontal extension and securing the lower end of the removable jaw; and a bolt 45 securing the upper end of the jaw to the head; said removable jaw having a forked upper end which fits the recesses.

40. The combination in a truck-frame, of flanged transoms; flanged side pieces; connection-angles which secure the webs of the transoms to the webs of the sides; gusset-plates 50 uniting the transoms and sides; and cast-metal pedestals with flanged jaws and necks each having flanges and a web, and each pedestal-neck being secured upon the inner surface of the end of a side piece and to the web and flanges only of the said side piece; the said 55 gusset-plates extending each side of the transom ends and to the necks of the pedestals.

41. A metallic pedestal having a longitudinally-perforated horizontal extension beneath the journal-box, a bolt in said perforation, a 60 removable end jaw perforated at the lower end and through which perforation the said bolt passes, and a nut upon the bolt.

42. A cast-metal pedestal having a longitudinally-perforated extension beneath the journal-box, said extension being rigid with the side frame, a perforated removable end jaw, and a longitudinal bolt and nut.

43. The combination with a truck-frame, of a rigid longitudinally-perforated horizontal extension beneath the journal-box; a removable end jaw having its upper end secured to the pedestal and its lower end perforated, a bolt located in the perforation of the horizontal extension and passing through the lower 95 end of the removable jaw, and a nut on the bolt.

44. The combination with a truck-frame, of a removable end piece which when in position interlocks with the pedestal-head, the lower 100 end of said jaw being secured in position by a bolt anchored longitudinally in a rigid horizontal extension beneath the journal-box.

45. The combination with a truck-frame having a rigid longitudinally-perforated extension beneath the journal-box, of a removable end jaw having its upper end secured to the pedestal and its lower end secured to the horizontal extension by a bolt located within 105 the perforation thereof; the lower end of the 110 jaw and the end of the horizontal extension interlocking.

46. The combination with a truck-frame having a rigid horizontally-perforated extension beneath the journal-box, of a pedestal-head extension projecting beyond the journal-box; and a removable end jaw detachably secured at its upper end to the pedestal-head extension and at its lower end upon the end face 115 of the horizontal extension by a horizontally-disposed bolt located within the perforation of the extension beneath the journal-box.

47. A pedestal comprising a spring-pocket, a perforated-head extension projecting from the pocket, a rigid horizontal extension beneath the journal-box provided with a longi- 120 125

tudinal perforation, a forked removable end jaw, a bolt and nut securing the top end of the jaw to the head, and a longitudinal bolt and a nut securing the lower end of the jaw to the horizontal extension.

48. A metallic pedestal having a recessed and perforated head, an end jaw with perforated forked members, and a bolt and nut; the arrangement being such that by tightening the nut the ends of the forked members may be sprung into frictional engagement with the surfaces of the recesses in the head; and means for anchoring the lower end of the jaw.

In testimony whereof we affix our signatures in presence of witnesses.

RANSOM C. WRIGHT.
FRANK E. STEBBINS.

Witnesses as to the signature of Ransom C. Wright:

LIZZIE REIFF,
WILLIAM C. STOEVER.

Witnesses as to the signature of Frank E. Stebbins:

JNO. T. MEANY,
ROWEN EDMONSTON.
